UNITED STATES PATENT OFFICE.

WALLACE W. ROBINSON, OF PORTLAND, MAINE.

STRAP TIGHTENER AND FASTENER.

1,324,927.

Specification of Letters Patent. Patented Dec. 16, 1919.

Application filed May 21, 1919. Serial No. 298,621.

To all whom it may concern:

Be it known that I, WALLACE W. ROBINSON, a citizen of the United States, residing at Portland, in the county of Cumberland 5 and State of Maine, have invented certain new and useful Improvements in Strap Tighteners and Fasteners, of which the following is a specification.

This invention relates to improvements in 10 strap tighteners and fasteners. It is more especially designed for use with straps or equivalent features to be used upon soft and yielding bodies, as the flesh of a person either direct or in connection with overshoes, 15 skates, etc.

One of its objects, among others, is to provide means whereby the rolling up and pinching of the flesh under the tightener and fastener during the tightening operation 20 is prevented.

In the drawings herewith accompanying and forming a part of this application, Figure 1 is a side elevation of my device used in connection with a strap shown in position before the lever is tightened; Fig. 2 is a side elevation of the same after the lever is tightened; Fig. 3 is a detail perspective view of the base; Fig. 4 is a detail perspective view of the tightener lever, and Fig. 5 is a detail perspective view of a modification of 30 the base.

The same reference characters indicate like parts in the several figures.

In said drawing 1 is a base having posts 9 35 intermediate its ends. The base is provided with a strap, or equivalent article, receiving opening 16 at one end. This opening may be provided with a closure 12, as shown in Fig. 3, if desired, or it may be in the 40 form of a recess, as shown in Fig. 5. The posts are provided with holes to receive studs 8 of a tightener lever 2. The tightener lever is provided with means for the attachment of the free end of a strap 13. 45 For this purpose it is bifurcated, as seen at 19, and has rotatably mounted therein on pivot 5 an antifriction roll 4 against which the strap registers. It also may have a toothed dog 3 pivotally mounted therein 50 on pivot 6, which normally tends to move toward the roll 4 and to hold the strap against accidental withdrawal. The rotation of the toothed dog 3 is limited by a stop 15, so that it will always be in ready position. It may carry a hand hold 7, if desired. 55 The base is provided with means for attachment of one end of the strap. This may be

a cross bar 11, and the end 14 of the strap, or any article used in the tightening operation, may be provided with an end hook 17 60 to engage said cross bar 11. The base may have spring arms 10 terminating in inwardly projecting beveled tongues 10', located in the path of the tightener lever when turned into tightened position, the tongues 65 10' being forced apart to admit said lever and hold it yieldingly in locked position.

It is noted that, when the free end of the strap 13 is inserted in the lever and the lever turned into tightened position, as shown in 70 Fig. 2, the strap passes under the roll between it and the toothed dog and the tension of the strap then tends to hold the tightener lever in locked position against accidental displacement. It is noted that the positioning of the posts in which the tightener lever is mounted intermediate the ends of the base causes it to present a long, broad bearing 75 surface beyond the bearing center of the lever and thus prevents the end of the base 80 from digging into the body, this being one of the important features of the invention.

I claim:—

1. In a device of the character described, a base, and a lever pivotally attached to said 85 base at a point spaced apart from one of its ends, said lever being provided with a strap adapted to engage the body to which the device is applied at a point intermediate the end of the base and the point of attachment 90 of said lever to said base.

2. In a device of the character described, a base having posts intermediate its ends, a strap receiving opening at one end and spring locking arms at the other end, and a 95 tightener lever pivotally mounted in said posts and adapted to carry one end of a strap, said lever being adapted to be turned on its bearing into locking engagements with said arms.

3. In a device of the character described, a base having a strap receiving opening at one end, yielding locking arms at the other end and a tightener lever pivotally attached to the base intermediate its ends.

4. In a device of the character described, a base provided with a strap receiving opening at one end and a tightening lever pivotally attached to said base and lying when untightened over said base and opening, said 110 lever being provided with means for engaging a strap.

In testimony whereof I affix my signature.
WALLACE W. ROBINSON.
